UNITED STATES PATENT OFFICE.

ANTON N. HORNUNG, OF LOS ANGELES, CALIFORNIA.

DESIGN FOR A REFRIGERATOR.

Application filed March 25, 1925. Serial No. 12,881. Term of patent 14 years.

To all whom it may concern:

Be it known that I, ANTON N. HORNUNG, a citizen of the United States, residing at Los Angeles, in the county of Los Angeles and State of California, have invented a new, original, and ornamental Design for a Refrigerator, of which the following is a specification, reference being had to the accompanying drawing, forming a part thereof.

Figure 1 is a front view of a refrigerator showing my new design.

Fig. 2 is a side view of the refrigerator shown in Fig. 1.

I claim:

The ornamental design for a refrigerator, as shown.

Signed at Los Angeles, in the county of Los Angeles, and State of California, this 17th day of March, 1925.

ANTON N. HORNUNG.
